United States Patent Office.

ALVA WORDEN, OF YPSILANTI, MICHIGAN

Letters Patent No. 77,233, dated April 28, 1868.

IMPROVEMENT IN WHIP-HOLDER.

The Schedule referred to in these Letters Patent and making part of the same.

TO ALL WHOM IT MAY CONCERN:

Be it known that I, ALVA WORDEN, of the city of Ypsilanti, in the county of Washtenaw, and State of Michigan, have invented a new and useful Improvement to Curtis Worden's Self-Adjusting Whip-Holder, which was patented on the twenty-second day of October, A. D. 1867, by Letters Patent of the United States, numbered 70,075, issued to H. M. Curtis and A. Worden, of Ypsilanti, Michigan, and which improvement consists in a clasp attached to the whip-holder, as a part thereof, for attaching the whip-holder to carriages; and I do hereby declare that the following is a full, clear, and exact description of the construction and operation of the same, reference being had to the annexed drawings, making a part of this specification, in which—

Figure 1 is a perspective view of the whip-holder and clasp attached complete, and attached to the dash-rod of a carriage, *a*.

Figure 2 is a sectional view of the whip-holder with the clasp attached, without the cap.

Figure 3 is a perspective view of the clasp complete.

Figure 4 is the cap to the clasp, detached.

Figure 5 is a screw, used in fastening the cap to the clasp.

The nature of my invention consists in making one of the jaws of the socket with a lateral extension or extensions adapted to fit the dash-board rod of a carriage, such extensions being homogeneous parts of said jaw, and serving, in connection with screw-caps, as a means of clasping the whip-socket in a firm position upon the said rod.

To enable others skilled in the art to make and use my invention, I will proceed to describe the same with reference to the drawings.

A represents the dash-board rod of a carriage. *B B'*, the jaws of a whip-socket, said jaws being shaped to receive a whip-butt between them, and opening and closing on a hinge-joint, *C*, as illustrated in the drawings. The jaws are made of light cast metal and of open work, as shown. *D D* are lateral extensions, cast on the jaws *B'*, at top and bottom. These extensions are made concave at their outer ends, so as to just fit the rod of the dash-board, as shown. *E E* are screw-clasps or caps, made concave on their inner faces, so as to fit the rod *A*.

It will be seen that when the whip-socket is placed against the rod *A*, and the caps or clasps screwed to the extensions, it will be firmly fastened upon said rod.

My invention saves the expense and inconvenience of having the socket made in two parts, that is, with a socket and a clasping-ring or rings separate from one another. Thus I am enabled to make a much cheaper and neater whip-socket and clasp combined, than heretofore.

What I claim as my invention, and desire to secure by Letters Patent, is—

Making the clasping-extension or extensions a part of one of the jaws of the whip-socket, and substantially in the manner and for the purpose herein described.

ALVA WORDEN.
